UNITED STATES PATENT OFFICE.

JAMES R. SWARTZ, OF INDIANAPOLIS, INDIANA.

NAILING DEVICE.

Application filed August 8, 1927. Serial No. 211,299.

The object of this invention is to improve, speed and cheapen the nailing of various articles. The invention has been made and developed particularly for use in nailing 5 metal case brooms, but it is not limited to such use.

One feature of the invention consists in providing means for driving a plurality of nails simultaneously into an article; and in 10 connection with this feature, the nails are placed in a frame which releasably holds them, so that the frame can be manipulated without displacement of the nails. This 15 enables the nails to be accurately located with reference to each other and to the contour of the article, as well as enabling them to be simultaneously driven. This greatly facilitates the nailing operation and, therefore, cheapens as well as improves the 20 product.

In using this improvement, the nails are partially driven into the article by force or 25 press head applied to the frame. Then the frame is removed and the nails completely driven in by force supplied to the nails themselves. Hence, two operations of the 30 nail driving means are required for driving the nails, one while the nail-holding frame is used and the other after it has been removed.

The full nature of the invention will be understood from the accompanying drawings and the following description and 35 claims:

In the drawings, Figure 1 is a plan view 40 of the nail-holding frame in position to receive the nails, parts being shown by dotted lines. Fig. 2 is a central vertical longitudinal section on the line 2—2 of Fig. 1 with the nails inserted in the nail-holding frame. Fig. 3 is a central vertical section 45 on the line 3—3 of Fig. 1 through the nail-holding frame and a broom and bed plate and press head with the parts in their positions at the end of the first nailing operation, parts being broken away. Fig. 4 is a 50 section similar to that shown in Fig. 3 with the nail-holding frame removed preliminary to the second nailing operation of the mechanism. Fig. 5 is a section the same as 55 shown in Fig. 4 at the end of the second nailing operation.

The nail-holding frame as it is herein shown consists of a plate 10 with a handle 55 11 extending from one end thereof, a plate 12 parallel with and spaced from the plate

10 and held in such relative and spaced relation by the screws 13, an intermediate locking plate 14 slidable in the space between said plates 10 and 11 and having longitudinal slots 15 through which said screws 13 extend, and a hammer or press plate 16 secured on the under or back side of the plate 10 when in the position shown in Fig. 2. The plates 10, 12 and 14 are provided each 60 with a plurality of nail holes or recesses 17 which register vertically with each other, but the hammer or press plate 16 has no nail holes in it. In Fig. 1 there are shown three 65 rows of nail holes, but so far as this invention is concerned, the number and arrangement of nail holes may be varied as desired. 70

In using the nail-holding frame, it is first 75 placed in its inverted position, as shown in Fig. 2, and nails 18 and 18^a are inserted in the nail holes head first. In the form shown 80 in Fig. 2, the heads of the nails rest on the hammer or press plate 16. Then the locking or sliding plate 14 is operated to lock 85 the nails in the frame. This may be accomplished by any suitable means, but as herein shown, it is accomplished by means of an eccentric 20 located in a corresponding recess in the locking plate 14 and lying between plates 10 and 12, as seen in Fig. 3, and the eccentric is turned by the eccentric lever 90 21 which projects through the plates 10 and 12, as shown. The parts are arranged so that when the locking plate 14 is in its unlocked position, as seen in Fig. 2, the lever 95 21 will extend inward as there shown, so that when the handle is turned away from that position or outward, as shown in Fig. 3, the eccentric will force the locking plate 14 inward, as shown in said figure, and thereby lock the nails in the frame. This 100 arrangement will enable the nail-holding frame to be manipulated or handled as desired without the nails falling out of the frame.

The nail-holding frame is then placed 105 upon the article to be nailed, which in Fig. 3 is a metal case broom 25, for the purpose of nailing the metal case 26 to the broom corn therein and the broom handle 27. The 110 article or broom is placed upon a bed plate 30 and then a press head 31 of a suitable press is brought down upon the nail-holding frame and particularly the hammer or press plate 16 thereof, and in the first nailing operation, the nails are driven in as far as the pressing or nailing machine will permit.

This first operation partially drives the nails as seen in Fig. 3, where the nails are driven about half way and at least sufficiently far to hold them in place in the article for the 5 second nailing operation.

After said first nailing operation, the press head 30 is elevated and the eccentric lever 21 is turned from the position shown in Fig. 3 to that shown in Fig. 2, which will 10 enable the nail-holding frame to be removed. The removed parts are then in the position shown in Fig. 4, the nails there appearing to be partially driven, so that the nailing paddle 33 is then placed upon the nails and 15 in the second operation of the press or nail driving means, the nails may be completely driven, as shown in Fig. 5. In that figure, the long nails 18 are shown as going through and turning back and clinching the material 20 within the case, while the short nails 18^a are shown in the handle of the frame. This 25 nails one side of a metal case broom as shown in Fig. 5 and the other side of the broom is subsequently nailed by a repetition of the foregoing operation, although that is not here shown.

This mechanism enables the nails to be accurately located with reference to each 30 other in the article to be nailed, and in articles like brooms to be always in the same relative positions to each other and to the lateral edges of the brooms so as to properly centralize the nails. This is a great improvement over the method of driving individual nails into such an article so that 35 they enter haphazard and in different places and positions in different brooms and often not centrally of the handle. Furthermore, this holder with the three plates, especially 40 with plates 10 and 13, serves to rather effectively guide the nails during the driving operation and this will tend to prevent them from going crooked as has been one of the 45 troubles in nailing metal case brooms heretofore. This enables one to drive a full set of nails on one side of the article or broom at one operation and simultaneously instead of the method heretofore employed in driving 50 nails singly into metal case brooms. This also enables a plurality of nails to be effectively held in place and manipulated after being locked and turned from one position to another, as shown, without any 55 escape or displacement.

The nail holes 17 are of different dimensions to suit classes of nails of different sizes, such as 18 and 18^a, so that the locking plate will simultaneously and equally engage all of the nails at the same time and lock 60 them. But sometimes the nails of the same class may vary to some extent and then the largest nail in such class will control the locking operation and the smaller nails are

liable not to be held tight. In order to 65 avoid any escape or displacement of such nails and to aid in holding the nails in the frame, the hammer or press plate 16 is preferably magnetized or made of magnetic metal so that it will magnetically hold the 70 nails in place in the frame.

What is shown herein is deemed the preferable construction of this invention, although it is not limited to the details shown. The hammer or press plate 16 might be omitted as the locking plate 14 75 would hold the nails in the frame, but said plate is preferable. Other means might be provided for holding the nails in the plate than that herein shown so as to accomplish substantially the same function. Likewise 80 nails may be driven by other means than the press head. The nailing paddle should preferably be as thick as the portion of the nail holder through which the nails had extended.

The invention claimed is:

1. A manually-controlled frame for holding 90 nails to be driven, having a pair of parallel plates secured together and spaced apart, a slidable plate between said pair of plates, said three plates having a plurality of series of nail holes registering with each other to receive the headed ends of the nails when inverted and leave the points of the 95 nails projecting beyond said frame, and means in said frame for manually moving said slidable plate for temporarily holding the nails in the frame while being partially driven and for thereafter releasing the nails so that the frame may be removed therefrom.

2. A frame for holding nails to be driven substantially as set forth in claim 1, and one of said plates being extended to form a handle for the frame.

3. A frame for holding nails to be driven substantially as set forth in claim 1, and a handle for said frame, the means for moving and holding said slidable plate being mounted in said handle.

4. A frame for holding nails to be driven substantially as set forth in claim 1, and a handle for said frame, the means for actuating said slidable plate comprising an eccentric in said handle, and a lever mounted in said handle and secured to said eccentric for operating the eccentric, substantially as set forth.

5. A frame for holding nails to be driven substantially as set forth in claim 1, and a hammer plate secured upon one of said first-mentioned pair of plates, substantially as set forth.

In witness whereof, I have hereunto affixed my signature.

JAMES R. SWARTZ.
